UNITED STATES PATENT OFFICE.

FRANK C. SMITH, OF TAMPA, FLORIDA.

RETAINING DEVICE FOR FILING CABINETS.

Application filed September 29, 1923. Serial No. 665,712.

To all whom it may concern:

Be it known that I, FRANK C. SMITH, a citizen of the United States, and a resident of Tampa, in the county of Hillsborough and State of Florida, have invented a new and Improved Retaining Device for Filing Cabinets, of which the following is a full, clear, and exact description.

This invention relates to filing cabinets and refers particularly to an improvement in a retaining device for locking the files, cards or other contents of said cabinet in place and against casual displacement.

The outstanding object of the present invention resides in the provision of a retaining device of this character which greatly facilitates the operation of locking or releasing the files, cards or other contents in place and minimizes the time and labor incident thereto.

As a further object the invention contemplates a retaining device for the contents of filing cabinets which is comparatively simple in its construction and mode of operation, inexpensive to manufacture and produce, and which is highly efficient in its operation.

With the above-recited and other objects in view the invention resides in the novel construction, combination and arrangement of the parts set forth in the following specification, pointed out in the claims and illustrated in the accompanying drawings, it being understood that variations and modifications which properly fall within the scope of the appended claims may be resorted to when found expedient.

Figure 1 is a fragmentary sectional plan view of a filing cabinet equipped with a retaining means constructed in accordance with the invention;

Fig. 2 is a fragmentary vertical sectional view thereof;

Fig. 3 is a detail perspective view of the locking means which coacts with the lock bar;

Fig. 4 is a fragmentary perspective view of the interengageable means on the lock bar which cooperates therewith;

Fig. 5 is a fragmentary transverse sectional view illustrating the lock bar in locked position relative to the file, card or other contents of the filing cabinet.

Referring to the drawings by characters of reference, 10 designates generally a fil-

ing cabinet or drawer having front and rear walls 11 and 12 and side walls 13 which connect the front and rear walls and are connected with a bottom 14 which is slotted as at 15 from the front to the rear wall. 60 The cards, files or other contents 16 are preferably provided with a guide 17 at the lower edge or that edge which is designed to rest upon the bottom of the cabinet or drawer. The guide 17 is formed with an open ring 18, and the lower edge of the guide which projects below the lower edge of the file or card 16 is adapted to project into the slot 15. The retaining device, which constitutes the invention and cooperates with the card, file or other contents constructed as heretofore set forth, consists of a flat lock bar 19 which is provided with a trunnion 20 at its rear end journaled in the bearing opening 21 in the rear wall 12 to allow for both turning and longitudinal sliding movements of the lock bar. In its forward end the lock bar is provided with an internal threaded socket 22 which is designed to receive the threaded extremity 23 of a short shaft section 24 journaled in the bearing opening 25 in the front wall 11 for rotary and sliding movements. The shaft section 24 projects through the bearing opening 25 and is provided at its outer free end with a manipulating knob or handle 26. The said shaft section 24 further functions when threaded into the socket 22 of the lock bar 19 as a second trunnion. The trunnion 20 also projects rearwardly beyond the rear wall 12 and its free outer end is engaged by a leaf spring 27 which normally exerts a force to effect a forward sliding movement of the lock bar. At its forward end the lock bar 19 is provided with teeth 28, preferably two in number, which extend beyond the forward end of the socket 22 and are disposed at diametrically opposite points. A locking plate 29, which is in the nature of a disk provided with diametrically projecting ears 30, is attached by screws or other fastening devices 31 to the inner side of the front wall 11, the central aperture 32 thereof being designed to align with the bearing opening 25 to permit of the projection of the shaft section 24 therethrough. The disk or plate 29 is provided in its inner face with right-angularly disposed pairs of aligned notches 33 and 34 which are adapted to re-

ceive the teeth 28 of the lock bar when the lock bar is rotated to a position to bring the teeth in registry with said notches. When in registry with the notches, the teeth are interengaged therewith due to the force exerted on the rear outer end of the lock bar trunnion 20.

Under this arrangement it will be seen that a retaining device for the contents of filing cabinets has been devised which may be readily manipulated to lock or release the lock bar by rearward pressure on the knob or handle 26 against the action of the spring 27 until the teeth 28 are retracted from the notches 33 or 34. When so re-

tracted, the operator by turning the knob 26 may dispose the lock bar with its major length vertical whereby the opening defined by the guide ring 18 may align with the minor thickness of the bar to permit of the withdrawal of the card, file or other contents. After the withdrawal and replacement of the file or card, the turning of the lock bar by the knob 26 to bring the teeth 28 into registry with the notches 33 will permit the spring 27 to function to reengage the teeth 28 with the said notches to hold the lock bar in locked relation to the guide ring 18.

30. What I claim is:

1. The combination with a filing receptacle, of a retaining member mounted therein, for longitudinal shifting and rotary movements, means operable upon movement of said member in one direction for locking the same against rotation, means for normally effecting longitudinal movement of said member in a direction for locking the same against rotation, and means connected with said member and extending through the receptacle to permit of manual shifting of said member longitudinally in the opposite direction whereby to release and rotate the same.

45. 2. A retaining device for the contents of filing cabinets, comprising a flat lock bar extending longitudinally of the cabinet and mounted therein for longitudinal and rotary movements, manipulating means extending through the forward end of the cabinet for manually effecting rearward sliding and rotary movement of the lock bar, means provided respectively at the forward end of the lock bar and the forward end of the cabinet 55 adapted for interengagement to retain the bar against rotation, and means for normally effecting the interengagement of said means.

60. 3. A retaining device for the contents of filing cabinets, comprising a flat lock bar

extending longitudinally of the cabinet and mounted therein for longitudinal and rotary movements, manipulating means extending through the forward end of the cabinet for manually effecting rearward sliding and rotary movements of the lock bar, a keeper plate secured to the inner side of the forward end of the cabinet having circumferential spaced notches, teeth at the forward end of the lock bar adapted for interengagement with the notches of the keeper plate to retain said bar against rotation, and means for normally effecting a forward longitudinal shifting movement of the lock bar to interengage said teeth with the notches.

4. The combination with a filing cabinet and articles adapted to be filed therein, each of which articles is provided adjacent its lower edge with a portion having a substantially keyhole-shaped opening through the lower edge of said portion, of a device for cooperating with said portion for retaining the articles within the cabinet or for releasing the same, comprising a flat lock bar extending longitudinally of the cabinet adjacent the bottom thereof and mounted therein for longitudinal and rotary movements, manipulating means protruding through the forward end of the cabinet for manually effecting the rearward sliding and rotary movements of the lock bar, means provided respectively at the forward end of the lock bar and the forward end of the cabinet adapted upon interengagement to retain the bar against rotation, and means for normally effecting the interengagement of said means.

5. A retaining means for the contents of filing receptacles consisting of a member having a rotary and reciprocatory movement in said receptacle, means associated with one wall of the receptacle and adapted for engagement with the member to prevent rotary movement thereof, and means associated with said member and adapted to move the same longitudinally to maintain operative engagement thereof with the first-mentioned means.

6. A retaining means for the contents of filing receptacles consisting of a member mounted therein for longitudinal and rotary movements, stationary means capable of being engaged by said member to prevent rotary movement of said member, and means for normally effecting longitudinal movement of said member to engage the same with the first-mentioned means.

FRANK C. SMITH.
